(57) CLAIM

The ornamental design for sports leggings, as shown and described.

DESCRIPTION

FIG. 1 is a front perspective view of a sports leggings design showing my new design.

FIG. 2 is a front view of the sports leggings.

FIG. 3 is a rear view of the sports leggings.

FIG. 4 is a left view of the sports leggings; and,

FIG. 5 is a right view of the sports leggings.

Any shading and cross-hatching are not features of the design but are utilized to illustrate the surface contours of the sports leggings design in the drawings.

1 Claim, 5 Drawing Sheets

FIG. 1

FIG. 2

FIG. 3

FIG. 4

FIG. 5
